UNITED STATES PATENT OFFICE.

EDWIN HARRISON, OF ST. LOUIS, MISSOURI.

FUME-CONDENSER.

SPECIFICATION forming part of Letters Patent No. 242,127, dated May 31, 1881.

Application filed July 24, 1880. (No model.)

To all whom it may concern:

Be it known that I, EDWIN HARRISON, of St. Louis, Missouri, have made a new and useful Improvement in Fume-Condensers, of which 5 the following is a full, clear, and exact description, reference being had to the annexed drawings, making part of this specification, in which—

Figure 1 is a view, in perspective, of the improvement; Fig. 2, a sectional elevation taken on the line $x\ x$ of Fig. 3; Fig. 3, a plan; Fig. 4, a vertical section taken on the line $x'\ x'$ of Figs. 2 and 3; Fig. 5, a horizontal section taken through the condenser on the line $x^2\ x^2$ 15 of Fig. 2, and showing the perforated disk; and Fig. 6, a detail, being a plan showing the slit-plate used in assisting the distribution of the fume-laden gas beneath the perforated sheet.

20 The same letters denote the same parts.

The present invention is an improvement in that class of fume- condensers wherein the smoke or fume-laden gas is purified by being passed through a body of water.

25 In this condenser the following results are obtained: As the gas is forced through the perforated disk (which may be of wood or metal) numberless bubbles are formed, great agitation of the water produced above the disk 30 in the chamber H, and a thorough breaking up and mixing of the gas and water effected, enabling the fumes to be properly washed, condensed, or arrested and retained by the water in the condenser, so that the body or volume 35 of fume-laden gas—from which the present apparatus is intended to extract the mechanically suspended or gaseous fumes coming from blast-furnaces, reverberatory furnaces, cupel-furnaces, or furnaces of any form or character

40 which may produce fumes—is made to present, in contact with the water through which it passes, many times as much surface as it would if forced into the water and allowed to escape in an unbroken body, and in proportion to the

45 thoroughness with which the body of fume-laden gas is broken up and its particles brought in contact with the particles of water is the efficiency of the condenser. Now, it is difficult to effect a thorough breaking up of the

50 gas-body in a body of water without employing a considerable depth of water through

which the bubbles of gas are to ascend; and the greater the depth to which the gas is forced below the natural level of the water before it is allowed to begin its ascent in the form of 55 bubbles the greater the amount of power required and consequent expense to force the gas against the head of water.

To obviate the difficulties named and to enable the smoke to be thoroughly brought in 60 contact with the water, and in such way as to reduce the resistance the smoke has to encounter in its transit to a minimum, is mainly the aim of this improvement, which is carried out as follows:

65 A represents the flue, through which the fumes in question are delivered to the condenser, B B B representing a series of any desired number of exhaust and pressure blowers, which receive the fumes from the flue and force them 70 through the pipe C into and through the condenser D; thence to escape through the discharge-pipe E, which, in turn, may lead back into the flue A or to any other desired point of final escape. The pipe C is of about the same size 75 and proportions as the flue A; but the chamber F of the condenser, into which the fumes are first delivered from the pipe C, is extended laterally to the full width of the condenser, from f to f, Fig. 3, for the purpose of enabling 80 the body of gas entering the condenser to spread itself out in a thin sheet over the water (shown at G, Fig. 2,) to the full width of the broad condenser; and just in proportion to the extent of such spreading of the gas above the 85 water can the depression of the water between the chambers F and H be reduced and the pressure of gas due to the head of water to be overcome be avoided.

85 In addition to the chamber F the condenser 90 contains a chamber, H, wherein the fume-laden gases enter, pass below, and emerge upward through the perforated plate K and the body of water which exists, and is sustained by displacement from the space I above said plate. 95 The chamber H may be higher than the chamber F, and should be high enough to prevent any considerable portion of water bubbles and spray from being carried up by the draft of the escaping gas into the flue E. The chamber H is of equal width with the chamber F and the space I, which connects the two cham- 100

bers. The space I between the chambers F and II is elongated horizontally in the direction of the passage of the smoke, separating the chambers F and II several feet apart.

5 The operation is as follows: The gas or smoke to be purified and the fumes to be condensed being forced by the blowers B B B B (or other suitable blowing apparatus) into the chamber F of the condenser, the solid particles that 10 have been mechanically sustained and carried along by the moving smoke partly drop into that part of the bottom of the condenser which is immediately beneath the chamber F. Those lighter portions of the fumes which to be condensed and arrested require to be so arrested by a more thorough washing of the smoke are carried along through the space I I'. At the farther end of this space a toothed plate, J, Figs. 2 and 6, is arranged. This plate is of the 15 shape shown more distinctly in Fig. 6, having a series of openings or slits, j j, which widen toward the end of the plate farthest from the chamber F, and the plate is fixed in the inclined position shown in Fig. 2. The office of 20 this plate is to prevent the flowing gaseous body from escaping from the space I immediately upward through that side of the perforated plate K which is nearest to the chamber F into the chamber II, and to cause it to be 25 more evenly distributed throughout the space under the plate K, and so that it shall pass up as evenly as possible through the openings k k of said perforated plate K. The latter is of metal or other suitable substance, and 30 is arranged in the condenser at the lower part of the chamber II, at or near the level of the space I', (the space I' is on a level with and is an extension beneath the chamber II of the space I,) and that serves to bring the gas 35 more thoroughly in contact with the water by breaking up the body of gas into innumerable bubbles, as above described. The water G G', when quiet, fills the space I I' and stands in the chambers F II at or slightly above the level 40 of the plate K. When the smoke is being forced through the condenser the effect is to depress the water in the chamber F and space I and to raise it in the chamber II. Owing, however, to the breadth of the condenser the 45 water-level needs to be depressed but a short distance—in practice but from a few inches to one foot. The water-level in the chamber II is correspondingly raised above the plate K, where it is kept suspended and agitated, as 50 aforesaid, by the pressure and upward current of the gas forced through it by the blowing machinery.

The present condenser is in use, being employed to purify the smoke of all kinds of mechanically-suspended metallic fumes and of all kinds of volatile and soluble salts, oxides, and acids, which pass off from the furnaces through the flue A, the blowers B B B B, the condenser D, and pipe E, to a chimney, (not shown.) The

flue A is beneath the ground surface a, and 65 when it is desired to use the condenser a gate, L, is let down to close the flue at a point between the blowers and the point where the pipe E re-enters the flue A.

The bottom of the condenser is formed into 70 a series of hoppers, M M M M, which taper, as shown in Figs. 2 and 4, and which are furnished with stop-cocks m m to enable the fume sediment and semi-fluid material which gathers in the condenser to be discharged from 75 time to time, as may be desired. By thus constructing its bottom the condenser can be expeditiously and economically cleaned.

The plate K is connected with the side h of the chamber II, but it does not extend entirely 80 across to the other three sides, h' h' h' of said chamber, and from the three edges of said plate next to said sides h' h' h', depends vertically an imperforate flange or apron, k', of sheet-iron or other suitable material dropping 85 from the said plate low enough to prevent the escape of the gas below the lower edge and to the outside of said apron. Said apron is also extended and attached to the sides of the condenser in, or nearly in, the line of the side h 90 of the chamber II, as shown at k², Fig. 2, in order to prevent the gas from escaping from the space I to the space outside of said apron. This apron also permits a downward current of fume-laden water next to and outside of the 95 apron, and so that the water may the more easily deposit its contents in the hoppers.

I claim—

1. The condenser D, having the plate J, having the openings j j, and the perforated plate K, combined and operating substantially as described.

2. In the condenser D, the inclined and toothed plate J, and the plate K, perforated, held, and extended as described, and provided 105 with the flange k', substantially as shown and described.

3. The condenser D, having the chamber II, space I', and plate K, said plate being perforated and extended as described, and provided 110 with the imperforate apron k', extending around the three edges of the plate K, substantially as described.

4. The condenser D, having the chambers F II and the space I I' of uniform width, and 115 elongated to separate said chambers, substantially as described.

5. The combination of the pipes C E and the condenser D, the latter having the chambers F II, water-space I I', plate J, and perforated plate K, said plate J having the openings j j, and said plate K being separated at three edges from the side of the chamber H, 120 substantially as described.

EDWIN HARRISON.
